[57] CLAIM

The ornamental design for a gliding rocker chair, as shown and described.

DESCRIPTION

FIG. 1 illustrates a gliding rocker chair incorporating the design of the present invention;

FIG. 2 illustrates a right side elevation view of the gliding rocker chair shown in FIG. 1, the left side elevation being a mirrored image thereof;

FIG. 3 illustrates a front elevation view of the gliding rocker chair of FIG. 1.

FIG. 4 illustrates a rear elevation view of the gliding rocker chair of FIG. 1;

FIG. 5 illustrates a plan view of the gliding rocker chair of FIG. 1, and .

FIG. 6 illustrates a bottom view of the gliding rocker chair of FIG. 1.

FIGS. 2, 3, 4 and 5 illustrate with phantom lines, cushions which are shown for purposes of environment only.

The broken lines shown on the seat pad in FIGS. 1 and 5 represent stitching. The fragmented depiction of fabric-like pattern shown on the chair pad in FIGS. 1 and 5 is understood to be continuous throughout.
